UNITED STATES PATENT OFFICE.

JOSEPH DICARLO, OF EDWARDSVILLE, ILLINOIS.

ICE CREEPER FOR SHOES.

Application filed April 22, 1920. Serial No. 375,767.

To all whom it may concern:

Be it known that I, JOSEPH DICARLO, a citizen of the United States, residing in the city of Edwardsville and State of Illinois, have invented new and useful Improvements in Ice Creepers for Shoes, of which the following is a specification, reference being had to the accompanying drawings.

This invention pertains to an attachment for shoes, in the nature of an ice creeper or anti-slip device.

The primary object is to provide a simple, efficient and durable attachment for the shoes of pedestrians, which will enable one to walk upon the ice or any slippery surface without danger of falling.

Another object is to provide the device in a form readily attachable to and detachable from the shoe.

A further object is to provide such a device stamped from a single piece of sheet metal and bent and punctured to form for use.

In the drawings:

Figure 1 is a side elevation of the device necessary to equip one shoe, same consisting of a heel plate and a toe plate.

Figure 2 is a top plan view.

Figure 3 is a frontal elevation.

Figure 4 is a rear elevation.

Figure 5 is a detail showing the method of attaching the straps to the toe plate.

Figure 6 is a plan view of the heel and toe elements spread out in sheet form.

In carrying out this invention, I provide a toe plate 1 formed from a single piece of sheet metal cut to form as shown in Figure

6. This plate is cut to conform to the forward portion or ball 2 of the shoe 3. The body of the plate 1 is perforated with a plurality of holes 4 which are punched downwardly so that the ragged edges 5 of the holes project downwardly as means for engaging the slippery surface. The outer edges

45 of the plate 1 are provided in oppositely disposed relation with a plurality of ears 6. These ears are formed integrally with the plate 1, being connected to the plate 1 at the points 7, while the free ends 8 of the ears

50 are adapted to be bent around and closed

upon the ends 9 of the straps 10 and 11; these ears are then riveted to the straps by rivets 12 which pierce through the ears and the ends of the straps. It will be noted that two of the ears are located at the toe of the plate 1, while two others are oppositely positioned at a medial point along the sides of the plate 1, and finally two are oppositely positioned at the rear end of the plate 1.

The strap 10 is formed in the shape of a Maltese cross, the rearwardly extending tongue 13 thereof being adapted to engage a buckle 14 which is mounted meditately upon the strap 11. The strap 11 is likewise composed of two parts joined together by a buckle 15. Thus the toe portion may be adjusted and secured to the shoe.

I likewise provide a heel plate 16, similarly formed from a single piece of sheet metal, as shown in Figure 6, and likewise 70 perforated with a plurality of holes 4 punched downwardly so as to afford ragged edges 5 to prevent the slipping of the heel. This heelplate is cut and shaped and consists of a bottom plate 17 and an upstanding 75 side strip 18 adapted to frictionally engage the heel 19 of the shoe 3. The side strip has integral connection with the bottom plate 17 at the rear point 20, is then bent forwardly past the integral side lugs 21, and 80 the integral front lugs 22, and the ends 23 of the side strip are bent and pinched in back of the lugs 22. The side strip 18 is then further locked by bending the top ends 24 of the lugs 21 and 22 down and outwardly and pinching these ends against the side strip.

The operation of the apparatus is obvious. Various sizes of the heel and toe plates would of course be made to meet demand. 90

While I have herein described a certain specific method of constructing and assembling the elements of my invention, it is understood same may be varied in minor details, not departing from the spirit of my 95 invention as defined in the appended claim.

What I claim to be new and patentable is:

An ice creeper for shoes, formed of a single piece of sheet metal, and including a heel plate, side strips having integral con- 100

nection with the heel plate at a central rear point, side lugs and frontal lugs; the said side strips being bent up and extended around the sides of the heel plate and bent partly across the front thereof; the side lugs being bent up and down over the side strips; and the frontal lugs being bent up and down

over the inwardly turned ends of the side strips.

JOSEPH DICARLO.
